UNITED STATES PATENT OFFICE.

FRANK J. WOOD, OF NEW YORK, N. Y., ASSIGNOR TO MARX & RAWOLLE, OF NEW YORK, N. Y.,
A CORPORATION OF NEW YORK.

PROCESS OF DISTILLING GLYCERIN.

No. 910,440.

Specification of Letters Patent.

Patented Jan. 19, 1909.

Application filed June 3, 1908. Serial No. 436,406.

To all whom it may concern:

Be it known that I, FRANK J. WOOD, of New York, in the county of Kings and State of New York, have invented certain new and useful Improvements in Processes of Distilling Glycerin; and I do hereby declare the following to be a full, clear, and exact description of the invention, such as will enable others skilled in the art to which it

10 appertains to make and use the same.

My present invention contemplates steps in the process of distilling glycerin consisting of returning to the still part of the steam from which the glycerin vapors have been 15 condensed, condensing the balance of the steam, and introducing a fresh supply of steam into the jet returning to the still, the live steam replacing the quantity of steam condensed and filling the additional office of 20 maintaining the circulation through the circuit.

The invention relates primarily to the distillation of glycerin containing impurities and fatty acids which emit foul odors in 25 vaporizing.

In Letters Patent No. 881,525 issued on my application March 10, 1908, and in an application for patent filed August 13, 1907, I have set forth a process, and shown appropriate means, of distilling glycerin having in view a saving in the consumption of steam necessary to distil a given quantity of glycerin. The idea present in both the patent and application referred to is the multiple 35 effect of a single steam supply, that is, conducting a single jet of steam successively to a plurality of stills and condensing the glycerin from each distillation.

The present invention seeks to effect economy of steam, not by conducting the single column to a plurality of stills, but by returning the steam to a single still after the glycerin vapors have been condensed. The presence of the impurities and fatty acids, 45 however, and the objectionable odor which they emit when vaporized, would render it impracticable to continue using the same steam in the still as this steam would carry a large portion of these vapors with it, they 50 not being condensed with the glycerin, and this objectionable element in the steam would obviously be increased as the distilling continued. To avoid this, and at the same time utilize repeatedly the column of steam, I 55 provide for condensing a portion of the

steam carrying vapors of the fatty acids or other impurities and adding to the circuit a supply of live steam equivalent to the amount condensed.

In the accompanying drawing I have 60 shown in conventional arrangement apparatus appropriate for carrying out the process, the figure being an elevation, partly in vertical section.

Referring to the drawing, 1 designates 65 the still and 2 the glycerin condenser. 3 is the steam condenser; 4 the evaporator; 5 the boiler and 6 the vacuum pump. All of these parts are or may be of any preferred construction and the application for patent 70 above referred to shows and describes in detail substantially the same form of still, condensers, etc. The still is shown equipped with an interior annular ledge 7 affording a central passage 8 and having a steam inlet 75 9 beneath the ledge and a glycerin inlet 10 above the ledge, the steam and glycerin being designed to enter the still in tangential lines of direction so as to cause them to whirl about and unite, thus effectively insuring 80 their physical association. The normal level of glycerin in the still is indicated at 12 and the glycerin is forced by a pump 13 into an initial heater 14 prior to its introduction into the still at 10, a pipe 15 conducting steam 85 to the heater from the boiler.

The glycerin condenser 2 is shown provided with a hot water space 16 through which extend vertical tubes 17, the normal level of the hot water in this condenser being indicated at 18. A pipe 19 is shown connecting the still to the glycerin condenser. The condensed glycerin is collected in, and removed from, the receptacle 20 beneath the condenser. From this receptacle a pipe 90 21 is shown leading to the steam condenser 3, a branch 22 thereof extending into the still. 23 is a steam nozzle leading from pipe 15 and opening into pipe 22.

The steam condenser 3 is, or may be, of 100 substantially the same construction as the glycerin condenser except that it is supplied with cold water as by a pipe 24. From the distillate receptacle 25 in the bottom of the steam condenser a pipe 26 connects the latter to the water space of the evaporator 4 while a pipe 27 connects the steam space of the evaporator with the space above the water level 18 of the glycerin condenser. This steam space of the evaporator is also 110

shown in communication with pipe 15 by a pipe 28, the latter having a throttle or reducing valve 29. This valve reduces the pressure from that of the boiler to about atmospheric as that is sufficient for evaporating the sweet water of low specific gravity as it comes down from the condenser 3.

The pressure in the steam space of the evaporator being about atmospheric the 10 pressure in the hot water condenser 2 will also be about the same, the size of pipe 27 being ample to take all the flow of steam from the condenser without back pressure.

30 is a condenser in communication with 15 the evaporator and having an outlet 31 leading to a sewer.

The vacuum pump 6 is shown in communication with the system for the purpose of reducing the pressure as well understood in the art.

In carrying out the process performed by the apparatus described, the steam from the boiler passing through pipes 15 and 23 enters the still and combines with the previously heated glycerin and the combined vapors pass to the glycerin condenser and through the tubes thereof. These tubes are surrounded by a body of hot water which is at a temperature sufficiently high to maintain the steam but low enough to condense the glycerin vapors so that the glycerin accumulates in the receptacle 20 and may be drawn off. The steam, carrying with it the vapors of the impurities and fatty acids, passes into pipe 21. A portion of this steam will enter the steam condenser 3 through the reduced passage way thereto, while the balance of the steam will pass through pipe 22 and back into the still. Before its entrance 40 into the still, however, this steam encounters the jet of live steam issuing from the nozzle 23 and consequently the steam supply is increased proportionately to the loss it may have occasioned by the quantity which passes 45 to the steam condenser. Thus the steam jet 23 supplies new steam and prevents the undue accumulation of gases from the impurities and fatty acids in the glycerin and also maintains the circulation between the still 50 and the glycerin condenser.

The water of condensation collected in the receptacle 25 passes through pipe 26 to the evaporator 4. The steam space of this evaporator which is at about atmospheric pressure is being supplied with live steam through pipe 28 reduced to atmospheric pressure by the throttle valve 29. I provide means for economizing in the amount of steam necessary to furnish the evaporator 60 by connecting its steam space by pipe 27 with the space in the glycerin condenser above the level of the hot water therein. When the glycerin condenses by passing through the tubes 17 it gives up so much 65 heat to the water surrounding these tubes

that this water readily boils and the steam thus generated is available for use in the evaporator or in other ways. The vapors from evaporator 4 are condensed at the condenser 30, the cold water supply pipe 24 being shown in communication with both of the condensers 30 and 3. This evaporator is normally operated with a vacuum in the liquor space, established by connection 32, and atmospheric pressure in the steam space. 75

I am aware that distilling processes have heretofore been known in which the fluid mingled with the element distilled is returned to the still and its use repeated. This is true in the distillation of hydrocarbons by 80 the action of air. But to repeat the use of a steam column in distilling glycerin it is essential that a portion of the steam be removed from the circuit and condensed owing to the accumulating entrainment of impure vapors, as previously explained, and also that the volume of the steam column be maintained by adding a quantity equal to that condensed.

I claim as my invention:— 90

1. The process of distilling glycerin consisting of supplying to the still a portion of the steam from which the glycerin vapors of a previous distillation have been condensed, and adding live steam to the steam supply. 95

2. The process of distilling glycerin consisting of condensing a portion of the steam from which the glycerin vapors of a previous distillation have been condensed, supplying the balance of the steam to the still, and adding live steam to the steam supply.

3. The process of distilling glycerin consisting of maintaining a circuit for a steam supply between a still and a glycerin condenser, condensing the glycerin vapors while 105 maintaining the steam, condensing a portion of the steam, returning the balance of the steam through the circuit into the still, and introducing live steam into the circuit in the path from the glycerin condenser to the still. 110

4. The process of distilling glycerin consisting of condensing a portion of the steam from which the glycerin vapors of a previous distillation have been condensed, supplying the balance of the steam to the still, and 115 evaporating the water of condensation.

5. The process of distilling glycerin consisting of combining steam and glycerin, condensing the glycerin in a hot water condenser, generating steam by the heat given 120 off by the glycerin in its condensation, maintaining the steam during the condensation of the glycerin, returning a portion of the steam to the still, condensing the balance of the steam and evaporating the water of condensation by the action of the steam generated in the condensation of the glycerin. 125

6. In a process of distilling glycerin, the steps of condensing the glycerin vapors in a hot water condenser in the presence of a 130

vacuum, the water space of the condenser being under atmospheric pressure, conducting the sweet water to an evaporator, and conducting to the steam space of the evaporator steam generated in the water space of the glycerin condenser.

In testimony whereof, I have signed this

specification in the presence of two subscribing witnesses.
